COIN-OPERATED FUEL ISSUING MACHINE

Gottlieb Looser, Zurich, Switzerland

Application February 4, 1949, Serial No. 74,648
In Switzerland November 30, 1948

1 Claim. (Cl. 222—2)

1
The object of the present invention is a fuel-issuing slot or prepayment machine which may be used, for instance, for filling cigarette, cigar or pipe-lighters with fuel.

The coil-operated fuel-issuing machine in accordance with the invention is designed on the principle whereby a fuel reservoir communicates with a cylinder and the latter communicates via a pipeline, with a delivery nozzle, a piston controlled by a coin-operated mechanism being movably arranged in said cylinder and impelling an accurately metered quantity of fuel to the delivery nozzle.

The enclosed drawing illustrates a typical embodiment of the invention, in which drawing:

Fig. 1 is a vertical section, whilst

Figs. 2 to 4 are details of the coin-operated mechanism.

The coin-operated fuel-issuing machine shown comprises a cabinet 1 closed at the top by a lid 2. In the cabinet 1 is accommodated a fuel tank or reservoir 3 which is in turn closed at the top by a lid 4. A cylinder 5 is mounted in the bottom of the tank 3, a pipe-line 6 being connected to said cylinder 5 and leading via a valve unit 7 and a ball-retaining valve 8 to the delivery nozzle 9. This nozzle is of such design (not shown in the drawing) that its outlet aperture opens automatically when a container to be filled is pressed up against said nozzle, whilst it also closes automatically when said container to be filled is removed from said nozzle. A pump-piston 10 mounted in the piston guide 11 and arranged on a piston-rod 12 co-operates with said cylinder 5. Said piston-rod passes through the lid 4 and is subject to the action of a spring 13 which bears at one end against a washer 14 which in turn bears on the lid 4, and at its other, lower end against a transverse cotter 15 in the piston-rod 12. The spring 13 tends to force the piston-rod 12 downwards, and thus to force the piston 10 into the cylinder 5. At its upper extremity the piston-rod 12 carries by means of a screw-thread 16 a forked element 17 the top of which is pierced by a spindle 18 on which a roller 19 is so mounted as to be loosely rotatable. One arm 20 of a bell crank 21 projects into said forked element 17, the other arm 22 of said bell crank bearing on a roller 36 of the coin-operated mechanism.

Said coin-operated mechanism is shown in detail, in various positions, in Figs. 2 to 4. As can be seen from Fig. 1, the coin-operated machine is provided with a chute 24 which leads downwards and to the rear the coin inserted through

the slot in the front wall of the machine. Below the aperture of the chute 24 a slot 26 is provided in a slide 25, so that any coin inserted into the slot of the machine and dropping rearwards down to the chute 24 is able to enter said slot 26. It is prevented from falling through said slot 26 by a pin 27 mounted in a position transversal to the longitudinal axis of said slide 25 and slidable in the latter. A leaf spring 28 which embraces the head of said pin 27 tends to maintain said pin in the position shown in Fig. 3. As this figure shows, said pin 27 is provided with a recess of slot 29 the breadth of which corresponds to the breadth of the slot 26. A spring 31 is secured to a pin 30 in the slide 25, the other end of said spring being fastened to a pin 32. Said spring 31 tends to draw the slide 25 in an outward direction, i. e., to the left in Figs. 2-4. At its extreme end the slide 25 carries a screw pin 33 on which the pressure or gripping unit 34 is fitted. By means of the latter the slide 25 can be moved against the resistance of the spring 31. In the slide 25 a roller 36 is mounted on a spindle 35. Said roller 36 is so mounted on the spindle 35 as to be slidable in an axial direction, and a spring 37 tends to press said roller against a wall 38. In this wall is provided a slot 39 the shape of which is illustrated in particular by Figs. 1 and 2. This slot has a circular extension 40 through which the annular flange 41 of the roller 36 can pass. A second, corresponding extension 42 (Fig. 1) is located in the slot 39. Behind the wall 38 a leaf-spring 54 is secured by means of a rivet 43, the shape of which is seen in Figs. 3 and 4.

2
The coin-operated machine functions in the manner described hereunder:
Assuming that the fuel tank 3 is completely or at least partly filled with fuel; if a coin is inserted into the chute 24, it falls on to the slot 26. If the coin inserted is too small, it automatically falls right through. If however, the coin is of the correct size required, it comes to rest on the pin 27. If the stud or button 34 is now pressed, thus sliding the slide 25, the head 44 is forced up against the guide surface 45 of the coin-insertion device. As is shown in Figs. 3 and 4, said guide surface 45 is so designed that it displaces the head 44, and with it the pin 27, in a transverse direction to the direction of movement of the slide 25, said displacement being all the greater the further said slide is moved to the right. At a given moment, the slot or recess 29 will coincide with the slot 26, the coin then dropping into a cashbox not shown in the draw-

ing. Whilst the coin, designated by the numeral 46 in Fig. 2, was bearing on the pin 27, it was brought, by the rearward motion of the slide 25, up against the retaining hook 47. The fore end 48, of hooked shape, of said retaining hook rests, when the mechanism is at rest, in a recess 49 in the slide 25. The rear end of the retaining hook 47 is subject to the action of a spring 50 the upper end of which bears against the bolthead 51. When the slide 25 containing the coin 46 is pushed back, said coin pivots the fore end 48 of the hook 47 in a clockwise direction, with the result that said fore end 48 is withdrawn from the slide 25, i. e., from the recess 49. Only when said retaining hook 47 is so deflected is a continuance of the inward movement of the slide 25 possible. When the coin 46 has, on this continued retracting movement, dropped through the slot 26 into the cashbox, and the pin 30 has impinged against the wall 52 of the coin-insertion device, the annular flange 41 has arrived in front of the extension 40 in the wall 38. In this position the spring 37 presses the roller 36 through the extension slot 40, so that said flange 41 comes to occupy a position behind the wall 38. As a result of this movement, the roller 36 slides away from under the arm 22 of the bell crank 21, thus releasing the latter. The result of this is that the rod 12 of the piston 10 can fall under the action of the spring 13. The comparatively powerful spring 31 returns all the parts to their initial position. On the return movement of the slide 25, the annular flange 41 moves along behind the wall 38. Towards the end of its outward movement, however, it is pressed by the left extremity of the leaf-spring 44 against the wall 38, and as soon as the annular flange 41 comes to lie behind the aperture 42 into the position illustrated in Fig. 3. The various components are now in their initial positions, and the arm 22 now again lies in front of the roller 36. On the release of the bell crank 21 by the roller 36 and the consequent downward movement of the piston 10 under the action of the spring 13, a quantity of fuel corresponding to the capacity of the cylinder 5 is forced into the pipe-line 6 leading to the delivery nozzle 9. The fuel is extracted from said

nozzle simply by pressing the container to be filled, such as a cigarette, cigar or pipe-lighter, up against said nozzle. This is effected by a known arrangement not shown in the drawing, by which for instance a sealing body, such as a ball, is lifted from its seating by a pin projecting from said nozzle.

As an additional feature a further mechanism may be provided which counts the number of strokes performed by the slide 25 and indicates the total directly on a scale, for instance, so that it is possible at any time to read off said scale the quantity of fuel which has already been extracted from the tank 3 and how much still remains therein.

What I claim is:

A coin-operated automatic fuel issuing machine comprising a fuel tank communicating with a cylinder and the latter communicating via a pipe line with a delivery nozzle, a piston and rod movably arranged in said cylinder for impelling an accurately metered quantity of fuel to the delivery nozzle, a coin-operated mechanism controlling the movement of said piston and rod, a spring, the rod of the piston being subject to the action of said spring and movable against the resistance of said spring, means including a slide for receiving a coin for controlling said spring, a roller mounted in the slide so as to be movable transversely of the direction of movement of said slide, a lever normally bearing on said roller for holding the piston rod in an initial position, said roller being withdrawn from below said lever thus releasing the lever which releases the spring for driving the piston rod, when a coin has been inserted and said slide pushed inwardly.

GOTTLIEB LOOSER.
